Inventor:

UNITED STATES PATENT OFFICE.

WILLIAM H. HOOKER, OF MANCHESTER, NEW HAMPSHIRE.

ROTARY ENGINE.

No. 861,725.

Specification of Letters Patent.

Patented July 30, 1907.

Application filed October 4, 1906. Serial No. 337,404.

To all whom it may concern:

Be it known that I, WILLIAM H. HOOKER, a citizen of the United States, residing at Manchester, in the county of Hillsboro and State of New Hampshire, have 5 invented new and useful Improvements in Rotary Engines, of which the following is a specification.

This invention relates to that class of fluid pressure engines known as "rotary" engines, and the object is to provide an engine of the character described which 10 shall be simple, efficient and economical, the same being adapted to the use of either an expansive or a non-expansive agent.

The invention consists in the combination and arrangement of parts set forth in the following specification 15 and particularly pointed out in the claims thereof.

Referring to the drawings: Figure 1 is a front elevation of my improved rotary engine. Fig. 2 is a side elevation of the same viewed from the left of Fig. 1. Fig. 3 is a sectional elevation taken on line 3—3 of Fig. 20 2 looking toward the left in said figure. Fig. 4 is an enlarged detail perspective view of the valve slide partly broken away. Fig. 5 is a longitudinal section of the valve slide. Fig. 6 is a section on line 6—6 of Fig. 1. Fig. 7 is a section on line 7—7 of Fig. 1.

Like numerals refer to like parts throughout the several views of the drawings.

In the drawings, 10 is a casing provided with two cylindrical piston chambers 11 and 12 located in opposite sides thereof. Cover plates 13 and 14 are bolted 30 to opposite sides, respectively, of the casing 10. The cover plate 13 is provided with an annular groove 15 in which is located a packing ring 16 formed of any suitable material and similarly the cover plate 14 is provided with an annular groove 17 in which is located a 35 packing ring 18.

Located within the piston chamber 11 is a rotary piston 19 and located within the piston chamber 12 is a rotary piston 20. The rotary pistons 19 and 20 are provided with hubs 21 and 22, respectively, said hubs 40 abutting face to face. An annular washer or packing ring 23 surrounds said hubs and prevents leakage of fluid from one to the other of the piston chambers 11 and 12. An exhaust passage 24, formed in the casing 10, is connected to the piston chambers 11 and 12. 45 The rotary pistons 19 and 20 are keyed to a shaft 25 to which a fly-wheel 26 and a cam 27 are also fast. The cam 27 is adapted to impart a reciprocatory movement to a valve-slide 28 on which is formed an admission valve 29 and a guide block 30. Stop valves 31 and 32 50 are mounted on the valve-slide 28 and are arranged to yield relatively thereto, said stop-valve 31 being provided with a spring 33 and said stop-valve 32 being provided with a spring 34, said springs acting to press said stop-valves downwardly against the peripheries 55 of the rotary pistons 19 and 20, respectively, and thereby preventing leakage of steam between the periph-

eries of said pistons and their respective stop-valves. As the pistons 19 and 20 and the stop-valves 31 and 32 become worn, their respective springs 33 and 34 take up the wear and thus always prevent leakage of steam. 60

A valve-chest 35, forming a part of the casing 10, is provided with a valve-chamber 36 formed therein in which the admission valve 29 is adapted to be moved right or left (Figs. 1 and 3). An inlet pipe 37 is adapted to convey fluid to the valve chamber 36, said fluid being either steam, water, air or the like as may be desired. The admission valve 29, as it is moved toward the right and left by the cam 27, is adapted to direct fluid from the valve chamber 36 into the piston chambers 11 and 12 alternately. The guide-block 30 is 70 guided in a recess 38 formed in the valve-chest 35.

The rotary piston 19 is provided with a projection 39 extending from the periphery thereof, said projection being provided with packing blades 40 and 41, each of which bears against the interior periphery of 75 the piston chamber 11 and against the sides thereof. The rotary piston 20 is provided with a projection 42 extending from the periphery thereof, said projection being provided with packing blades 43 and 44, each of which bears against the interior periphery of the piston chamber 12 and against the sides thereof. The packing blades 40, 41, 43 and 44 may be formed of any suitable material which will prevent leakage of fluid past said blades. 80

When the valve-slide 28 is reciprocated by the cam 85 27, the stop-valves 31 and 32 are moved into and out of the paths of the projections 39 and 42, respectively, it being understood that when the stop-valve 31 is moved into contact with the periphery of the rotary piston 19, the stop-valve 32 is moved out of contact 90 with the periphery of the rotary piston 20 and vice versa. The stop-valve 31 when in contact with the periphery of the rotary piston 19, as illustrated in Fig. 6, forms an abutment against which the fluid acts, said fluid being under pressure acting to move the 95 projection 39 away from said stop-valve, thereby imparting a rotary movement to the piston 19.

If a non-expansive agent be employed the admission valve 29 may remain in the position shown in Fig. 3 until the projection 39 reaches the exhaust passage 24, 100 said projection 39, in passing said exhaust passage, allowing the fluid to pass outwardly therethrough, but if an expansive agent be employed the admission valve 29 may be closed before said projection 39 has reached said exhaust passage, thereby allowing the imprisoned 105 expansive fluid to expand until said projection has passed said exhaust passage. Similarly when the valve 29 is moved to the position shown in dotted lines (Fig. 3) the fluid is permitted to pass through the inlet pipe 37 into the piston chamber 12, said fluid acting on the 110 projection 42 of the piston 20 in the same manner as described in connection with the projection 39 of the

rotary piston 19. The stop-valve 31, when moved out of engagement with the periphery of the rotary piston 19, passes into a recess 45 formed in the cover plate 13 and in like manner the stop-valve 32, when moved 5 out of engagement with the periphery of the rotary piston 20, passes into a recess 46 formed in the cover plate 14. The metal forming the bottom of the recess 45 is beveled downwardly at 45' and the metal forming the bottom of the recess 46 is beveled downwardly 10 at 46', as shown in Fig. 3. The bottom of the recess 51 is lower than the bottom of the recess 45 and similarly the bottom of the recess 52 is lower than that of the recess 46. By reason of the bevels 45' and 46' and the location of the bottom of the recesses 51 and 52 as 15 above described the stop-valves 31 and 32 are free to be pressed into close contact with the peripheries of the pistons 19 and 20, respectively, by their respective springs 33 and 34. As the pistons 19 and 20 become reduced in diameter because of wear, the stop valves 20 31 and 32 still press against the peripheries of their respective pistons 19 and 20 and thus at all times prevent leakage of steam between the peripheries of said pistons and their respective stop valves. For the proper lubrication of the pistons 19 and 20, oil may be 25 fed in any suitable manner to oil chambers 47, 48, 49 and 50. The valve slide 28 is provided with oil slots 53 and 54 extending therethrough.

When the stop-valve 31 is in its extreme right-hand position, its left-hand side is still in engagement with 30 the recess 45 and its right-hand side is in engagement with a shallow recess 51. By reason of this construction, leaking of fluid past the sides of the stop-valve is effectually prevented. Similarly when the stop-valve 35 32 is in its extreme left-hand position its right-hand side is still in engagement with the recesses 46 and its left-hand side is in engagement with a shallow recess 52.

Having thus described my invention, what I claim and desire by Letters Patent to secure is:

1. In a rotary fluid pressure engine, a casing provided with a piston chamber and two recesses located on opposite sides, respectively, thereof, a cylindrical rotary piston located in said chamber, said piston provided with a projection extending from its periphery, an admission valve adapted to admit fluid to said chamber, a slide adapted to reciprocate longitudinally of the axis of rotation of said piston, a stop-valve carried by said slide, and a spring adapted to press said stop-valve toward said piston, said stop-valve adapted to engage both of said recesses simultaneously, said recesses being so formed and arranged that said stop-valve when in engagement therewith is adapted 45 to be pressed by said spring against the periphery of said piston.

2. In a rotary fluid pressure engine, a casing provided with two piston chambers, cylindrical rotary pistons located in said chambers, respectively, each of said pistons provided with a projection extending from its respective periphery, an admission valve adapted to admit fluid to said chambers alternately, a slide adapted to reciprocate longitudinally of the axes of said pistons, two stop-valves carried by said slide, and springs adapted to press said 50 stop-valves against the peripheries of said pistons, respectively.

3. In a rotary fluid pressure engine, a casing provided with two piston chambers, cylindrical rotary pistons located in said chambers, respectively, each of said pistons provided with a projection extending from its respective periphery, an admission valve adapted to admit fluid to said chambers alternately, a slide adapted to reciprocate longitudinally of the axis of said pistons, said slide provided with two recesses, two stop-valves located in said recesses, respectively, and springs adapted to press said stop-valves against the periphery of said piston, respectively.

In testimony whereof I have hereunto set my hand in presence of two subscribing witnesses.

WILLIAM H. HOOKER.
